UNITED STATES PATENT OFFICE

RUSSELL H. BOWEN, OF PHILADELPHIA, PENNSYLVANIA, ASSIGNOR TO THE AMERICAN PULLEY COMPANY, OF PHILADELPHIA, PENNSYLVANIA, A CORPORATION OF PENNSYLVANIA

TRUCK

Application filed January 21, 1929. Serial No. 333,842.

This invention relates to trucks, more particularly to hand trucks such as ordinarily used in handling freight in loading and unloading railroad cars and ships, as well as in transporting heavy or bulky packages in manufactories, warehouses, etc.

More specifically, my invention is concerned with hand trucks having bodies made from sheet metal; and in such connection I aim to secure the utmost strength and rigidity with employment of a minimum amount of material. This end is attained as hereinafter fully set forth, through provision of an open frame with side bars and intermediate longitudinals connected at intervals by a number of transverse or cross bars.

My invention is also in part directed toward provision of supplemental means for reinforcing the truck frame where additional strength is desirable, or where distortion is likely to occur through forcible contact with solid obstructions under rough usage.

In general, I aim to secure the advantages of structural lightness and manufacturing economies resultant upon employment of sheet metal in the construction of hand trucks.

Still other objects and attendant advantages of this invention will appear from the detailed description which follows of the typical embodiment shown in the attached drawings whereof Fig. I is a front elevation of my improved hand truck.

Fig. II is a side view of the truck with portions broken out and in section to emphasize certain important details.

Fig. III is a detail cross section taken as indicated by the arrows III—III in Fig. I.

Figs. IV and V are sections taken as indicated respectively by the arrows IV—IV and V—V in Figs. I and II.

Fig. VI is a detail section taken as indicated by the arrows VI—VI in Figs. I and V.

Figs. VII and VIII are perspective views of supplemental members which I provide to reinforce the truck frame at certain regions; and

Fig. IX is a detail section taken as indicated by the arrows IX—IX in Fig. II.

As herein delineated, the hand truck of

my invention embodies a top frame comprehensively designated by the numeral 10, the same being in the form of a die stamping struck from a single piece of sheet metal with slightly divergent side rails or bars 11, 11 and an intermediate longitudinal 12, which side bars and longitudinal are joined at intervals by a series of transverse or cross bars 13, 14, 15. From Fig. IV it will be observed that the side bars 11 are of hollow channel cross section open at the bottom, and moreover that they rise well above the plane of the transverse bars 13—15, thereby better adapting the truck for support and retention of convex surfaced packages like barrels for example. Along their lower edges the lateral faces of the side bars 11 are outwardly joggled as at 17, 18 with formation of stiffening beads, whereof in each instance, the former is round and the latter square as shown in Fig. IV. The cross bars 13—16 are likewise of invert channel cross section as exemplified in Fig. III, their depending edge flanges 19 having a depth corresponding to that of the inner beads 18 of the side bars 11, and their tops formed with depressed medial embossments 20 for greater rigidity. The longitudinal 12 has a cross sectional configuration exactly like that of the transverse bars 13—16, but its medial embossment 21 terminates short of the embossments 20 of said transverse bars with avoidance of intersections as is manifest from Fig. I.

Into the hollows of the side bars of the frame 10 at one end of the truck are fitted the squared shanks of handles 22, which are preferably constructed from wood and bowed or rounded for convenience and comfort in gripping them.

As a means to reinforce the upper cross bar 13 of the frame, I provide a supplemental bar 25 having a counterpart channel cross section dimensioned to fit within the hollow of said transverse bar, as seen in Fig. VI. The supplemental bar 25 is stiffened by an upward medial embossment 26 which is adapted to contact with the embossment 20 of the transverse bar 13 when the parts are assembled as shown in Fig. VI. The ends of the supplemental bar 25 are flattened as at 27, 27 to 100

bridge the open bottom of the side bars 11 while contacting with the lower faces of the shanks of the handles 22. As shown in Figs. I, II and V, the handles 22 are secured by bolts 28 passing centrally down through aligned apertures 29, 30 respectively in the tops of the side bars 11 of the frame, and the bridging ends 27 of the supplemental bar 25. I may also employ in each instance an additional transverse bolt 31 to pass through the lateral faces of the side bars 11 and render the fastening of the handles 22 more secure.

At the forward end of the truck, the top surfaces of the frame side bars 11 are depressed somewhat as at 32 for substantially flush fitment of the rearwardly turned ends 33a of the toe piece 33. As depicted, this toe piece is fashioned to the conventional form from stout bar metal and secured by rivets 20 or bolts 34. The wheels 35 of the truck are mounted on the cylindrically turned trunnion ends 36a of a square axle 36 secured to drop brackets 37 which engage within the hollows of the side bars of the frame and have their feet 37a secured by the same bolts or rivets 34 that serve the toe piece 33.

In the intervals between the ends of the shanks of the handles 22 and the drop brackets 37, the open bottoms of the channelled side bars 11 of the truck frame are closed by cover strips 38 whereof one is shown in perspective in Fig. VIII. From the latter illustration as well as from Fig. IV it will be observed that the cover strips 38 are of channel cross section and have their side flanges 39, 40 so disposed angularly as to coincide with and fit into the beads 17, 18 of said side bars. After assembling, the strips 38 may be permanently secured by welding their edges to the contiguous edges of the frame side bars 11.

To insure against collapse of the frame side bars 11 under forcible impacts incidentally to rough usage of the truck I employ, at intervals along their lengths, lateral bracing means in the form of tubular spacers 41 around bolts or rivets 42 with heads lapping the outer faces of said side bars, see Figs. I, II and IX.

From the foregoing it will be apparent that my invention affords a hand truck which is light in weight yet strong and rigid, and conducive to manufacture in quantity at small cost. It is of course to be understood that, if desired, more than one intermediate longitudinal may be provided between the side bars of the truck frame; and, that all or more of the cross bars may be reinforced by supplemental bars if the exigencies of practice should so dictate. It is to be further understood that the strips 38 may be employed as reinforcing elements independently of the spacing collars 41 and vice versa, and moreover that said strips may be made shorter and several of them used at spaced intervals along the side bars 11 of the truck

frame—all without departing from the spirit of my invention as defined in the appended claims.

Having thus described my invention, I claim:

1. In a truck of the character described, a body frame of intersecting inverted channels die stamped from a single piece of sheet metal, and comprising side channels or sills substantially deeper than wide, and interconnecting cross channels materially wider than deep lying substantially in the plane of the lower edges of said side channels and having their webs reversely channelled or longitudinally embossed forming a load-retaining cradle between the sills, whereby maximum load accommodating depression of their tops is secured and maximum stiffness of the cross members is combined with minimum depth.

2. In a truck of the character described, a body frame of intersecting inverted channels die stamped from a single piece of sheet metal, and comprising deep side channels or sills and shallow interconnecting cross channels lying substantially in the plane of the lower edges of said side channels and having their webs reversely channelled or longitudinally embossed forming a load-retaining cradle between the sills, whereby maximum load accommodating depression of their tops is secured and maximum stiffness of the cross members is combined with minimum depth, together with shallow intermediate longitudinals extending from cross channel to cross channel substantially in the same plane and having their webs reversely channelled or longitudinally embossed to afford maximum stiffness combined with minimum depth, the reverse embossment of said longitudinals terminating short of the cross channels to avoid impairment of the stiffening of the latter by their reverse embossment.

3. In a truck of the character described, a body frame constructed integrally from sheet metal with hollow side bars of inverted channel cross section joined at intervals by a series of cross bars, the lateral faces of said side bars being formed with outwardly joggled stiffening beads along their edges; and lengthwise reinforcing strips of sheet metal with their longitudinal edges engaging the beads of the side bars and closing the open bottoms of the latter.

4. In a truck of the character described, a body frame constructed integrally from sheet metal with hollow side bars and transverse bars connecting the side bars at intervals, said transverse bars being of inverted channel cross section; and a supplemental sheet metal reinforcing bar of channelled cross section reversely arranged and fitted into the hollow of one of the transverse bars aforesaid.

5. In a truck of the character described, a

body frame constructed integrally from sheet metal with hollow side bars, and transverse bars connecting the side bars at intervals, said transverse bars being of inverted channel cross section and stiffened by depressed medial embossments in their top faces; and a supplemental sheet metal reinforcing bar of reversely channeled cross section fitting the hollow of one of the transverse bars and having an upward medial embossment in its bottom face in contact with the embossment of said transverse bar.

6. In a truck of the character described, a body frame constructed integrally from sheet metal with hollow side bars of inverted channel section joined at intervals by cross bars likewise of inverted channel cross section; handles with their shanks engaged in the hollows of the side bars at one end of the truck; a supplemental bar of reversely channeled cross section fitting into the hollow of the rearmost cross bar of the body frame, the ends of said supplemental bar being flattened to bridge the hollows of the side bars in contact with the bottoms of the handle shanks; and bolts extending down through aligned apertures in the tops of the side bars and in the flattened ends of the supplemental bar to secure the handles.

20 7. In a truck of the character described, a body frame constructed integrally from sheet metal with hollow sides bars of inverted channel section; handles with their shanks engaged in the hollows of the side bars at one end of the truck; brackets for wheel axles engaged in the hollows of the side bars of the frame at the opposite end of the truck; and reinforcing strips also of sheet metal closing the open bottoms of said side bars in the intervals between the handle shanks and the wheel axle brackets.

In testimony whereof, I have hereunto signed my name at Philadelphia, Pennsylvania, this 14th day of Jan., 1929.

RUSSELL H. BOWEN.
